APPARATUS FOR DECORATING BOTTLES,
JARS, CANS, AND LIKE ARTICLES

Julian S. Gravely and Leon N. Kersey, Wilmington, Del., assignors, by mesne assignments, to Bond Manufacturing Corporation, Inc., Wilmington, Del., a corporation of Delaware

Application June 20, 1933, Serial No. 676,636

12 Claims. (Cl. 101—38)

Our invention relates to improvements in process of and apparatus for decorating bottles, jars, cans and like articles. In general, our invention has to do with providing a process and apparatus by means of which labels, and like decorative designs, may be printed directly upon bottles, jars, cans and like articles.

Heretofore, it has been the general practice to apply labels, and like designs, to bottles, jars, cans and like articles by pasting printed labels thereon. Such articles, as generally manufactured of glass, tin plate and similar materials, are not formed to precise dimensions and will show variations in their wall thickness as well as imperfections and irregularities upon the surface portions to which the label or decoration is to be applied which, though usually slight, nevertheless have heretofore precluded the adoption of known printing and lithographing methods for applying labels and decorative designs to such articles.

In the case of tin cans, it has been proposed, and some manufacture has taken place in accordance therewith, to lithograph the label, or design, on a sheet of tin plate before it is made into a can. This requires, however, that the side seam of the can be soldered from the inside, a slow and expensive process which adds considerably to the cost of such a decorated can. Other methods that have been and are being used to some extent in applying designs and labels to bottles, jars, cans and like articles are applications of the decalcomania process, rubber stamps and spray processes carried out with the use of means for shielding portions that are not to be decorated. These methods are essentially hand operations and do not lend themselves to large scale automatic or semi-automatic machine operations.

We are also aware of the fact that, for many years, it has been customary to print the labels, or decorative designs, directly upon the walls of collapsible tubes. The collapsible tube, however, is made of material so soft that it has an easily yielding wall and any slight irregularities in the wall are ironed out by the pressure to which the tube is subjected during coating and printing. Moreover, in the manufacture of collapsible tubes, the wall thickness is maintained substantially uniform throughout. Collapsible tubes, therefore, present quite a different problem than bottles, jars and cans, which have walls that are either rigid and unyielding, as in glass and similar ceramic materials, or relatively unyielding and resistant to deformations for correcting sur-

face irregularities, as in the case of cans made of tin plate and similar materials. Furthermore, bottles, jars and cans vary considerably in wall thickness. It is not unusual to find variations of as much as a sixteenth of an inch in the wall thickness of individual bottles of the same shipment. Such variations in the thickness of unyielding walls are bound to produce imperfect impressions, when one attempts to print thereon, unless some means are provided to compensate automatically for the differences in wall thickness.

One of the principal objects of our invention, therefore, is to provide a process of and apparatus for automatically compensating for variations in the thickness of unyielding or relatively unyielding walls in applying decorative coatings to or printing directly on bottles, jars, cans and the like articles.

A further object of our invention is to provide a process of and apparatus for compensating for imperfections and irregularities upon the surface portions of the bottles, jars, cans and like articles in applying decorative coatings or printing directly on such articles.

A further object of our invention is to provide a process of and apparatus for applying decorative coatings or printing directly upon selected portions of the surface of bottles, jars, cans and like articles wherein the articles to be treated are fed automatically to and past a coating or a printing station and while positioned at such station are automatically manipulated to bring the surface to be coated or printed upon into the correct relationship, all while automatically compensating for any variations in the wall thickness or imperfections or irregularities in the surface portions that are to be coated or printed upon.

Another object of our invention is to provide means whereby the article to be printed upon or coated may be rotatably supported and positioned during the printing operation.

Further objects, and objects relating to details and economies of our process and apparatus will definitely appear from the detailed description to follow. In one instance, we have accomplished the objects of our invention by the devices and means described in the following specification. Our invention is clearly defined and pointed out in the appended claims. The preferred instrumentalities for carrying out our process are illustrated in the accompanying drawings, forming a part of this specification, in which:

Figure 1 is a view, partly in side elevation and partly in vertical section on the line 1—1 of Fig. 2,

of mechanism for applying the ground coating to the articles in carrying out the first step of our improved process;

Fig. 2 is a fragmentary, top plan view of the mechanism illustrated in Fig. 1;

Fig. 3 is a perspective view of one of the work-holders for rotatably supporting and positioning the article to be coated;

Fig. 4 is a detail, sectional view taken on the line 4—4 of Fig. 1, showing a bottle supported in a work-holder and receiving the ground coating;

Fig. 5 is a fragmentary view in elevation, showing a modified form of work-holder supporting a shorter bottle in position to receive the ground coating;

Fig. 6 is a fragmentary view, partly in side elevation and partly in section, illustrating the application of the ground coating to the bottle shown in Fig. 5;

Fig. 7 is a view similar to Fig. 5, but showing a modified form of work-holder rotatably supporting a tin can in position to receive the ground coating;

Fig. 8 is a view in end elevation of the work-holder shown in Fig. 7;

Fig. 9 is a detail, sectional view, showing the spring-pressed pin in the work-holder of Fig. 3, for releasably retaining the bottle neck in position;

Fig. 10 is a fragmentary view in side elevation, illustrating the application of a ground coating to a small bottle or jar, supported by a work-holding mandrel;

Fig. 12 is a detail, sectional view taken on the line 12—12 of Fig. 10;

Fig. 13 is a detail sectional view, corresponding to Fig. 12, but illustrating a form of mandrel without any resilient surface covering;

Fig. 14 is a detail, sectional view, corresponding to Fig. 12, but illustrating a work-holding mandrel for use with small glass jars, having a resilient surface covering of cork;

Fig. 15 is a similar view, illustrating a cork-covered mandrel for use in supporting glass vials;

Fig. 16 is a similar view, illustrating a plain mandrel for supporting a glass vial;

Fig. 17 is a view, in side elevation, of a cork-covered mandrel for engagement with the interior of a bottle, or jar, to be coated, showing how the driving roll may be formed integrally with the cork covering of the mandrel;

Fig. 18 is a view in side elevation of mechanism which may be used in carrying out the printing step of our process;

Fig. 19 is a top plan view of the carrier portion of the mechanism shown in Fig. 18, the transfer cylinder being removed and the frame of the machine shown in section;

Fig. 20 is a fragmentary view, in end elevation, of the mechanism shown in Fig. 18;

Fig. 21 is a detail sectional view taken on the line 21—21 of Fig. 18, showing the printing of a label directly upon the side wall of a bottle;

Fig. 22 is a detail sectional view taken on the line 22—22 of Fig. 21;

Fig. 23 is a detail sectional view taken on the line 23—23 of Fig. 18;

Fig. 24 is a fragmentary top plan view showing the resiliently supported platform and the adjacent portions of the conveyor frame;

Fig. 25 is a perspective view of the platform;

Fig. 26 is a perspective view of the type of work-holder particularly adapted for bottles;

Fig. 27 is a fragmentary detail view, corresponding in general to Fig. 21, but illustrating a work-holder rotatably supporting a tin can to receive the imprint;

Fig. 28 is an end view of the work-holder shown in Fig. 27;

Fig. 29 is a view, corresponding to Fig. 21, but illustrating a work-holder of the mandrel type for supporting a small bottle; or jar, to receive the imprint;

Fig. 30 is a view in side elevation of a modified form of mechanism particularly suited for stripping tumblers;

Fig. 31 is a sectional view on line 31—31 of Fig. 30, and

Fig. 32 is a sectional view taken on line 32—32 of Fig. 31.

In the drawings, the same reference numerals refer to the same parts throughout the several views, and the sectional views are taken looking in the direction of the arrows at the ends of the section lines.

In general, the process of our invention consists in applying a ground coating to a portion of the wall of the bottle, jar, can, or like article, having relatively unyielding walls, which is to be decorated and, then, printing upon said ground. While this ground coating may function to promote adherence of the printed design applied thereto, it does not necessarily have such function but may serve merely as a background for the printed design or cooperate with the printed colors in forming a composite design or decoration. We have used the term "ground coating" in the latter, broad sense, wherever it occurs in the specification or claims. Our invention contemplates the application of the ground coating to the wall of the article by any desirable means. For instance, this ground coating may be applied by a spraying operation. However, we prefer to use, as the instrumentality for applying the ground coating, a coating machine, which applies the ground by rolling contact between a coating roller and the rotatably mounted article. We contemplate the use of a gelatin-covered coating roller, as this provides a soft and yielding surface, which in most cases may compensate for the variations in wall thickness of the article to be coated. We propose, also, to use special work-holding devices carrying the articles to be coated and holding them in contact with the surface of the coating roller. In many cases, these devices may advantageously consist of means for positioning and rotatably supporting the article to be coated, by external contact with such article. Our invention contemplates printing upon the ground coating thus applied to the article, by any suitable mechanism, but we prefer to use an offset printing machine, having incorporated therein special devices by which the articles to be printed are rotatably supported and resiliently presented to contact with the transfer cylinder. In some cases, we may print directly upon the article without applying a ground coating thereto. The ground coating is preferably an enamel and the design may be printed in any suitable ink. However, in cases where it is desirable to prevent the decoration, or design, from being washed off by the action of solvents used in cleaning the bottles, and the like, we propose to print the design in ceramic inks and fire the article after the design has been printed thereon, to fix the enamel and the ink. In such case, any enamel used for the ground coating should be of such a nature as to

stand firing and become indurated thereby. The article, of course, has to withstand firing also.

Our invention contemplates, further, an improved coating apparatus, including a coating roller and a turret, or carrier, having mounted thereon a plurality of work-holders for the articles to be coated, the movement of said turret carrying the articles into contact with the coating roller and maintaining them in said contact during the coating operation. We propose to use, in most cases, work-holders which rotatably support and position the articles to be coated through external contact therewith, thus avoiding errors through variations in the wall thickness of the article. We prefer to use a gelatin-covered coating roller, because the yielding surface of this roller in most cases will compensate for variations in wall thickness and surface irregularities of the article. In some cases, we may use a work-holder of the mandrel type engaging the interior of the hollow article to be coated; and, in that event, we prefer to use a mandrel having a resilient surface covering, which helps to compensate for variations in wall thickness and also functions to transmit power applied for rotating the articles during the coating operation. We propose to use, in some cases, an internal mandrel of smaller diameter than the hollow article to be coated, so that the article rolls upon the mandrel while in contact with the coating roller.

Our invention contemplates, further, an improved offset printing apparatus, of such a nature that the article to be printed is resiliently presented to contact with the transfer surface of the cylinder of the printing mechanism. We propose to provide a carrier, having thereon a plurality of work-holders in which the articles to receive the imprint are rotatably supported, and said carrier may be intermittently advanced to present the articles successively in contact with the transfer surface of said cylinder. We contemplate the use, as a carrier, of an endless conveyor, which passes over a resiliently supported platform opposite the cylinder. We propose to mount a plurality of work-holders upon said endless conveyor, so that the work-holder carrying the article, while the latter is in contact with the transfer surface of the cylinder, engages the resiliently supported platform.

Referring to the numbered parts of the drawings, we have shown in Figs. 1 to 17, inclusive, mechanism which may be used in practicing the coating step of our process. The coating machine is best shown in Figs. 1 and 2, in which there is illustrated a frame 10, provided with standards 11, supporting the coating roller and the feeding mechanism therefor, and standards 12 supporting the work-holding disk, or carrier, and the driving mechanism therefor. A shaft 13, journaled in the standards 11, carries the coating roller 14, having a covering 15 of gelatin on a portion of the surface thereof. Whenever, in the specification and claims, we refer to a "gelatin" covering for the coating roller, we use the term to define generally that class of ink-applying rollers which are made of some soft composition and may be gelatin, soft rubber, or any one of the many special compositions that have been developed in the printing art. A sprocket 16, fixed on the shaft 13, is rotated by means of the chain 20, passing thereover and around a sprocket 18, fixed on a shaft 17, which is journaled in the main frame 10 of the machine. A gear 19, fast on the shaft 17, meshes with a pinion 22, which is fast on a shaft 21 journaled in hangers de-

pending from the main frame 10. The shaft 21 carries a pulley 23, around which passes the driving belt 24, transmitting power to the machine. Thus, it will be seen that the coating roller 14 is rotated by power transmitted from the belt 24, through pulley 23, shaft 21, pinion 22, gear 19, sprocket 18, chain 20 and sprocket 16.

Upon the standards 11, there is provided a reservoir 25, which contains the enamel or other coating material. A shaft 27, journaled in bearings carried by the standards 11, carries a roller 26, which dips into the material in the reservoir 25. The roller 26 contacts with another roller 28, carried by shaft 29, journaled in bearings supported by the standards 11, and the latter 15 roller contacts with the gelatin-covered surface 15 of the coating roller. A gear 30 on the shaft 27 meshes with a pinion 31 on the shaft 29, and the latter meshes with a gear 32 fast on the shaft 13. Accordingly, as the coating roller revolves, 20 the feeding rollers 26 and 28 will be caused to revolve with it, thus feeding coating material to the surface of the coating roller. The adjusting bolts, screwed into portions of the frame and provided with hand wheels 33 and 34, are provided 25 for adjusting the bearings of the shafts 27 and 29, so as to regulate the contact between the rollers 26, 28, and the coating roller 14. A drive roll 35 is fixed on the shaft 13 adjacent one end of the coating roller, and this drive roll 30 preferably has a surface of cork, or like friction material. A guard 36 is fixed to one of the standards 11, and surrounds a portion of the periphery of the drive roll 35, so as to prevent the latter from being coated with the material fed 35 to the coating roller.

A work-carrying disk, or turret, 38 is fixed on the shaft 37, which is journaled in the standards 12 of the main frame. This disk carries a plurality of work-holders, which will be described 40 hereinafter, and receive an intermittent motion through the following mechanisms. A ratchet wheel 40 is fixed on the shaft 37, and is engaged by the pawl 41, pivoted at 42, to the end of a walking beam 43, which is journaled on the 45 shaft 37. The opposite end of the walking beam 43 is connected by link 44 to an eccentric pin 45 carried by the side of the gear 19. As the gear 19 revolves, therefore, the disk 38 will be moved intermittently due to the ratcheting of 50 the pawl 41 over the ratchet wheel 40. As illustrated, the disk 38 carries three work-holders, while the ratchet wheel 40 is provided with six teeth, so that there are six steps in a complete rotation of the disk 38. This is to allow the operator more time for placing articles in the work-holders. It is to be understood that more or less work-holders may be used, as desired, this being a matter of operation generally dependent upon the size, shape and kind of article, and the facilities for its manipulation.

As shown in Fig. 1, three work-holders are mounted upon the disk 38, so that, at every other step of movement of the disk, the article carried by one of the work-holders will be brought into 65 contact with the coating roller. The means by which these work-holders are mounted upon the disk is best shown in Fig. 4. The work-holder itself is shown in the perspective view, Fig. 3. An L-shaped bracket 46 is fastened to the disk 70 38 by means of the bolts 47. The base 48 of the work-holder rests upon the portion of the bracket 46 extending at right-angles to the disk 38, and is secured thereto by the bolts 49. At one end of the base 48, a member 50 is secured, which is 75

provided with a notch 51, adapted to receive the neck 52 of the bottle 53. A spring-pressed pin 55 is provided, which projects, normally, from one side of the notch 51, so as to engage the neck 52 of the bottle and releasably retain it within the notch. As shown in Fig. 9, a recess 54 is formed in the member 50, and the spring-pressed pin 55 has an enlarged end 56, which is lodged in the recess 54, the pin 55 projecting from said recess through a bore leading thereto. A spring 57 is compressed between the enlarged end 56 and a plate 58 secured to the member 50 by a bolt 59, and closing the open side of recess 54. Thus, when the bottle neck 52 is placed in position, the pin 55 will be pushed in and, then, automatically projected above the neck of the bottle, as shown in Fig. 9, so as to releasably retain it in position. The base of the bottle 53 is supported and positioned by a disk, or plate, 60, having a peripheral flange 61, of such size that the base of the bottle fits snugly within it. A trunnion 62 projects from the base 60, and is journaled in the member 63, which is fastened to the end of the base 48 opposite the member 50. A driving roll 64 is fixed on the projecting end of the trunnion 62, and adapted to engage the driving roll 35, when the work-holder is in position to present the article carried thereby to contact with the coating roller.

It will be understood that the size and construction of the work-holder depends somewhat upon the character of the article, which is to be held thereby for contact with the coating roller. In Fig. 5, we have shown a slightly modified form of work-holder adapted to support a bottle 53a, which is smaller and shorter than the bottle 53 shown in Fig. 4. This work-holder includes a rotatable plate journaled in the member 63a, and having a peripheral flange 61a fitting the base of the bottle 53a. A driving roll 64a is also provided for contact with the driving roll 35, when the bottle is presented to contact with the coating roller. The work-holder also includes a member 50a, which is secured to the base 48 and provided with a notch 51a, receiving the neck of the bottle, which is retained therein by the spring-pressed plunger 55a. The member 50a, instead of being secured to the end of the base 48, as in Fig. 4, is fastened to said base intermediate the ends hereof, as shown in Fig. 5.

In Figs. 7 and 8, we have illustrated a form of work-holder which is adapted for supporting a tin can. This includes a base 65, which is fastened to the projecting portion of the bracket 46. At one end of the base 65, there is fastened an upstanding arm 66. A supporting plate 67 of such size to fit snugly within the end of the can 70 is provided with a trunnion 68, journaled in the member 66, and a driving roll 69 is fastened to the projecting portion of said trunnion, so as to contact with the driving roll 35, when the can 70 is presented to contact with the coating roller. A part 71, having a pair of spaced hinge lugs 72, is fastened to the other end of the base 65. A member 75 is provided with a hinge ear 73, which fits between the hinge lugs 72, to which it is hinged by means of the pin 74. A supporting and positioning plate 78, of such size as to fit within the corresponding end of the can 70, is journaled in the member 75 by means of a trunnion 77. A ring 76 fixed on the projecting end of said trunnion prevents displacement of plate 78. It will be seen that the member 75, carrying the supporting and positioning plate 78, can be swung to one side, as shown in dotted lines, to permit the

insertion and removal of the can 70. When the can has been inserted in the holder, the member 75 is swung from the dotted line to the full line position, whereupon the can is rotatably positioned and supported by the holder, by means of the external contact of the plates 71 and 78 within the projecting flanges at the ends of the can 70.

In some cases, as when the article to be coated is a small jar, the work-holders may take the form of a mandrel engaging the interior of the jar, or other hollow article to be coated. As shown in Figs. 10 and 11, a plurality of spindles 80 are mounted upon the disk 88, and sleeves 81 are rotatably mounted upon said spindles. A mandrel 82 is secured to the outer end of the sleeve 81, and is provided with a resilient surface covering 83, of rubber or the like. The size of this mandrel and its resilient surface covering is such as to permit it to pass through the mouth of the jar and engage the interior thereof, as shown in Fig. 12. A driving roll 85 is fastened to the sleeve 81, said driving roll being adapted to contact with the driving roll 35, when the jar 84 is presented to contact with the coating roller 16. It should be noted that the external diameter of the mandrel 82, and its covering 83, is less than the internal diameter of the jar 84, so that the jar rolls upon this mandrel, while in contact with the coating roller. The provision of the resilient covering 83 upon the mandrel, together with the gelatin-covered coating roller, will constitute a sufficient compensation for irregularities in wall thickness of the jar 84. At the same time, the resilient covering tends to increase the frictional contact between the article and the mandrel and to prevent slippage of the article when driven during the coating operation. In some cases, it is unnecessary to provide the resilient covering 83 upon the mandrel and, then, we may use a holder such as shown in Fig. 13, in which the mandrel 86 is rotatably mounted upon the spindle 80, and is provided with an enlarged portion 87, contacting with the interior of the jar 84a, and with a shoulder 88, against which the mouth end of the jar engages, to position the jar accurately upon the mandrel. In some cases, we propose to use a mandrel having an external, resilient, surface covering of cork, as illustrated in Figs. 14 and 15. As shown in Fig. 14, a cork mandrel 90 is mounted upon the exterior of the revolving sleeve 81, which mandrel engages snugly the interior of the jar 84b, and supports the same. There is sufficient resilience in this cork mandrel to compensate for variations in thickness of the wall of the jar 84b. The cork covering may also function as an aid in driving or rotating the article, as when the mandrels are positively driven. The cork forms an excellent medium for transmitting drive to the article. In Fig. 15, we have shown a similar form of mandrel adapted for use with long vials. In this case, the cork sleeve 91 is mounted upon the exterior of the rotatable sleeve 81 carried by the spindle 80. In some cases, this cork sleeve will not be necessary for the coating of glass vials, in which event, the revolving sleeve 81 may engage directly the interior of the glass vial 84c. But, in this case, the sleeve 81 is formed of such diameter as to allow a clearance 92 between its outer surface and the interior of the vial 84c, so that said vial will roll upon the mandrel 81 while in contact with the coating roller.

In Fig. 17, we have shown a form of construction in which the cork mandrel 93 may be formed integral with a cork driving roller 95, the two being separated by a reduced neck 94, and mount-

ed as a unit upon the revolving sleeve 81, carried by the spindle 80. In this way, a cork roll is provided for engagement with the driving roll 38, and an excellent, frictional driving surface is provided.

The mechanism heretofore described for the application of a ground coating may, in some cases, be used as a printing mechanism by the substitution of transfer means for the coating roller.

From a description of the parts heretofore given, the operation of this mechanism in carrying out the coating step of our process will be readily understood. As the carrier disk 38 revolves intermittently, the operator places the bottles, or articles to be coated, in the work-holders carried by said disk, and the rotation of the disk advances the articles carried by the work-holders into contact with the coating roller, when the work-holder assumes the position shown in Fig. 1, at the right hand side of the carrier disk. While the carrier disk is at rest with the article in the holder in contact with the coating surface 15 of the roller 14, which revolves continuously, coating material will be fed from the reservoir 25 to the coating roller, and will be spread uniformly upon the surface of the wall of the bottle, or article, rotatably supported and positively driven in the holder. At the end of the period of rest, the disk 38 will rotate and carry the coated article away from the coating roller to a position in which it may be removed from the holder by the operator, while another article is presented to the coating roller for coating. Thus, the bottles, jars, cans, or like articles, rotatably supported in the holders of the carrier disk, will be provided with a coating of enamel, or other coating material, uniformly applied, notwithstanding variations in the wall thickness and surface irregularities of the article, and the relatively unyielding character of these walls.

In some cases, it is desirable to clean the surface of the bottles, or other articles, before they are coated and, to this end, we have provided a plate 96 on which is mounted a pad 97 of felt, or like material. The plate 96 is provided, at one end, with an arm, which is pivoted at 98, to a post 99, fixed on the frame 10. The other end of the plate 96 has a depending ear 103, to which is pivotally connected at 104 a threaded rod 100, extending through a bracket 101, carried by the frame. A spring 102 is compressed on said rod 100 between ear 103 and bracket 101, which spring tends to urge the plate 96 upwardly, so that, as the disk 38 rotates, the bottles, or other articles, in the holders are carried with a rolling and wiping motion across the felt pad 97, which cleans the surface to be coated. The nut 105 on rod 100 limits upward movement of plate 96.

It will be understood that the extent of the area to be coated will be determined by the length of the cylindrical band of gelatine covering 15 upon the coating roller, as best shown in Fig. 2.

Although, in many cases, we prefer to use a coating machine of the character described, for carrying out the first step of our process, that is, the application of a ground coating to the bottle, jar, can, or like article to be decorated, still, other instrumentalities and means may be used for this step. For instance, in some cases, the ground coating may be sprayed upon the portion of the wall of the article which is to be decorated. Other methods of applying this ground coating may be used.

For carrying out the second step of our proc-

ess, that is to say, the printing of the required design upon the ground coating previously applied to the wall of the bottle, jar, can, or like article to be decorated, we prefer to use an offset printing mechanism, which may be of the multicolor type. Such an offset printing mechanism would include the usual plate cylinders and transfer cylinder and, also a work-carrying mechanism, which is especially constructed, so that variations in the wall thickness or surface irregularities of the articles to be printed upon will not affect the accuracy of registry, or result in imperfect printing.

Referring to Figs. 18 to 29, inclusive, in which we have illustrated such an offset printing mechanism, forming the preferred means for carrying out the second step of our process, we have shown, in Fig. 18, a printing mechanism comprising the frame 116, in which there is journaled the shaft 119, carrying the transfer cylinder 111. Arranged around the periphery of the transfer cylinder, are the usual plate cylinders 112 with their ink-feeding mechanisms. A rubber blanket 113 is stretched over a portion of the surface of the cylinder 111, forming the transfer surface of said cylinder. A gear 114, fast on shaft 119, meshes with a pinion 115 on shaft 116, the latter carrying a pulley 117, around which passes the belt 118, transmitting power to run the machine. As shown in Fig. 20, there is a belt shifter 106, pivoted at 107, and connected by a link 108 with the lever 109, pivoted on the frame, at 134. To the lower end of this lever there is connected a rod 135, which passes out through the frame at the front of the machine, and is provided with a handle 136, by which the rod 135 may be moved longitudinally to shift the belt 118 from the loose pulley to the fast pulley 117, on shaft 116. An eccentric pin 120, on the end of shaft 119, is connected by link 121 with the mechanism for imparting intermittent motion to the work-carrier, which mechanism will be described hereinafter. The portion of the offset printing mechanism heretofore described is substantially the same as that illustrated in United States Letters Patent to A. J. Ford, No. 1,092,830, for Printing press, patented April 14, 1914, and needs no further description here.

In order to make use of an offset printing mechanism of this character for printing directly upon bottles, jars, cans, and like articles, having relatively unyielding walls, it has been necessary for use to devise a novel form of work-carrier, by means of which the work to receive the imprint may be resiliently presented to contact with the rotating transfer surface of the cylinder. This novel work-carrier is constructed as follows:

Four posts 122 are connected to form a rigid frame work by means of the members 123. At the upper end of each post, there is mounted a rod 124, provided with right and left hand threads, and to which a hand wheel 126 is fixed, so that the rod may be rotated easily. The upper portions of the rods are screwed into the cross-bars 125, while the lower portions, threaded in the opposite direction, are screwed into the nuts 127 fixed at the tops of the posts 122. Thus, the posts 122 support the two cross-bars 125, and the frame work carried by said cross-bars may be leveled at each of the four corners thereof, by adjustment of the hand wheels 126. This permits a fine adjustment of the carrier, so as to insure proper alignment of the work with the

transfer cylinder to secure a perfect impression. A pair of angle-bars 128 rest upon and are secured to the cross-bars 125, and said angle-bars 128 constitute the side members of the carrier frame. These two angle-bars are spaced apart a sufficient distance to permit the work-holding conveyor to run between them. The sprocket shafts 129 are journaled in said side members 128, at opposite ends thereof, and, on each shaft 129, a pair of spaced sprockets 130 are fixed. A pair of spaced endless chains 131 run over these sprockets 130, as shown in Figs. 18 and 19. A plurality of base plates 132 are carried by the endless chain 131, being located between these chains and pivoted thereto by means of the trunnion pins 133, carried by the chains and journaled in the base plates 132, as illustrated in Figs. 21 and 23. Angle-bars 138 are carried by the side members 128, by means of bolts 137 and spacing sleeves 138, in such a way that the base plates 132, carried by the upper reaches of the chains 131, may rest upon and ride over the rails formed by the upper legs of the angle-bars 138. This arrangement is best shown in Figs. 19, 21, 22 and 23. The rails 139 are interrupted opposite the transfer cylinder, as shown in Figs. 19 and 22, in order to provide room at that point for a resiliently supported platform, upon which the base plate and the work-holder carrier thereby may rest, while the article in the work-holder is in contact with the transfer surface of the cylinder. Angle-bars 140 are carried by the side members 128 by means of hangers 142, and constitute guide rails for the lower reach of the conveyor, these angle-bars being of such size as to support the base plates 132 on the lower reach of the conveyor, as best shown in Fig. 21. At both ends, the angle-bars 140 are curved around in an arc, as at 141, so as to accommodate the swinging movement of the base plates 132, as the chains 131 pass around the sprockets.

As already stated, a resiliently supported platform is provided, opposite the transfer cylinder, upon which the base plate 132 of the work-holder may rest, while the article carried by it is in contact with the transfer surface of the rotating cylinder 111, so that the article is resiliently presented to contact with the transfer surface. This platform 143 is shown, in perspective, in Fig. 25, and also illustrated in Figs. 21, 22 and 24. The platform 143 has the end portions 144 reduced in thickness to accommodate the chains 131. Depending from the lower surface of the platform 143, are the four posts or legs 145, which project through holes formed in the horizontal flanges of the angle-bars 128. Nuts 147 are screwed on the lower ends of the posts 145 and limit the upward movement of the platform 143 with respect to the frame. Surrounding the bolts 145 are the coil springs 148 compressed between the lower surface of the platform 143 and the upper surfaces of the horizontal flanges of the side members 128, whereby the platform is resiliently supported from said frame. Guide blocks 149 are fixed to the vertical legs of the angle-bars 128, as shown in Figs. 21 and 24, and said guide blocks 149 fit in notches 150 at opposite ends of the platform 143, whereby said guide blocks, and the posts 145, confine the movement of the platform 143 with respect to the frame to a vertical movement, and thus prevent its moving out of the proper registry.

In order to provide for proper registry of the base plate 132 with the platform 143, upon which it rests during the printing operation, the upper

surface of the platform 143 is provided with a rib 151, which has its leading end 152 tapered or pointed, and which rib fits snugly within a notch 153 formed in the lower surface of the base plate 132. The pointed, or tapered, end 152 of the rib helps to guide the base plate 132 into proper registering position upon the platform 143, in which position it is securely held during the printing operation. An angle-bar 154 is fixed to the front side member 128, at a point adjacent 10 the platform 143, and the horizontal leg of said angle-bar overhangs the chain and the front edge portion of the platform 143, and base plate 132 thereon, as shown in Fig. 21.

It will be apparent, therefore, that we have 15 provided a frame work in which is mounted an endless conveyor, comprising a plurality of pivoted base plates, which are advanced with the conveyor until they reach a point opposite the transfer cylinder, at which time, the base plate 20 engages a resiliently supported platform in perfect registry therewith. The means for intermittently advancing this endless conveyor are as follows: The end of link 121 is pivoted, at 155, to an arm 158 journaled on a shaft 159 carried by 25 the frame. The pivot pin 155 also carries a pawl 157, which co-operates with a ratchet wheel 158, fast on shaft 159. Shaft 159 also has secured thereto a gear 160, which meshes with a pinion 161 on the adjacent sprocket shaft 129. Thus, the 30 sprocket shaft 129 is rotated so as to advance the conveyor intermittently, it being understood that the gearing is so designed that, at each step, the conveyor will be advanced a distance sufficient to bring the next work-holder on its base plate 132 35 into printing position.

We have shown a work-holder mounted upon each of the base plates 132 of the conveyor. Of course, it is not necessary to mount a work-holder on each base plate. For instance, if it is desired 40 to provide more time in which the operator can place bottles, or other articles, in the work-holders, work-holders may be omitted from certain of the base plates, as, for example, every other one of them. With a conveyor of the endless 45 chain type, however, we believe that there will be sufficient opportunity for the operator to place articles in the work-holders before they reach the printing position, so that a work-holder can be provided on each of the base plates. Fig. 26 50 shows a work-holder, of the form which we propose to use for bottles, mounted upon one of the base plates 132. This form of work-holder, with a bottle mounted in position, is also shown in Fig. 21. It comprises a base 162, which is fastened to the base plate 132 by the bolt 163. To one end of the base 162, there is fastened the upright member 164, in which a supporting and positioning plate 165, provided with a peripheral flange 166, is journaled. The plate 165 and flange 166 are of such size that the base of the bottle A to receive the imprint will fit snugly within the flange. From the opposite face of the plate 165, there extends a trunnion 167, journaled in the member 164, and a ring 168, fixed to the 60 projecting end of trunnion 167, prevents displacement of the rotatably mounted supporting and positioning plate 165. To the other end of the base 162, a member 169 is fastened, which is provided with a notch 170 to receive the neck of 65 the bottle A. This notch is of such form as to provide lateral support only for the neck, it being so deep that the neck does not touch the bottom thereof. Between the members 164 and 169, a support 171 is fastened to the base 162, 70 75

which support contacts with the wall of the bottle A just above the decorated portion thereof, as shown in Fig. 21.

In Figs. 27 and 28, we have illustrated a form 5 of work-holder especially suitable for use with tin cans, having projecting peripheral flanges at top and bottom. This work-holder comprises a base 162, fastened by the bolts 163 to the base plate 132. To one end of the base 162 there is fastened 10 a member 172, in which the supporting and positioning disk 173 is journaled. The disk 173 is of a size to fit within the projecting flange at the end of can B, as shown in Fig. 27, and is provided with a trunnion 174, which is journaled 15 in member 172. A ring 175 fixed on the projecting end of the trunnion 174 prevents displacement of the rotatable supporting and positioning disk 173. To the other end of the base 162, a member is fixed, which is provided with a pair of hinge lugs 175'. A member 176 has projecting therefrom a hinge ear 177, which fits between the hinge lugs 175' and is hinged thereto by the pin 178. The supporting and positioning disk 179 is journaled in the member 176, and is of such 20 size as to fit snugly within the projecting flange at the corresponding end of the can B, as shown in Fig. 27. The disk 179 has a trunnion 180 projecting therefrom, which is journaled in the member 176, and a ring 181 fixed on the projecting 25 end of said trunnion, prevents displacement of the positioning and supporting disk 179. It will be observed that the member 176, and the parts carried thereby, can be swung to dotted line position, as shown in Fig. 27, to permit removal or 30 insertion of a can.

We also contemplate the use of a holder of the mandrel type in this machine, and such an arrangement is shown in Fig. 29, in which a member 182 is fixed to one end of the base 162. The 35 member 182 carries a spindle 183, on which the mandrel 184 is journaled, said mandrel having a resilient surface covering 185, of rubber or like material, which contacts with the interior of the jar C to be decorated. The external diameter of the mandrel 184, and its covering 185, is such 40 that it will pass through the mouth of the jar C, and is less than the internal diameter of said jar, so that the jar rolls upon this mandrel under 45 rolling contact with the transfer surface of the cylinder. The base 162 is mounted on a base plate 132, as in the other forms of work-holders shown, so that, the jar is resiliently supported 50 against the transfer surface of the cylinder by the resilient platform on which the base plate 132 rests, when in position for printing, and, also, by the resilient surface covering 185 of the mandrel. This we have found to be sufficient to compensate 55 for variations in the wall thickness of the jar C and for surface irregularities and imperfections. In a similar manner, work-holders of the 60 forms shown in Figs. 13 to 17, inclusive, may be used, mounted on the base plates 132.

The operation of this offset printing mechanism 65 will be apparent from the description of the parts given above, and it will be evident therefrom how the printing step of our process is carried out. When the belt 118 is shifted onto the fast pulley, so that the machine is driven thereby, the transfer cylinder 111 rotates continuously. The carrier mechanism is advanced intermittently. As 70 the transfer cylinder rotates in the direction of the arrow, Fig. 18, the transfer surface 113 passes over the plate cylinders 112, which apply ink to its surface arranged in the required design. The 75 continued rotation of the cylinder brings this

transfer surface into contact with the article held by the work-holder opposite said cylinder and, as this transfer cylinder rolls in contact with said rotatably supported article, the ink arranged in the required design on the transfer surface is transferred to the ground on the wall of said article. Due to the pawl and ratchet mechanism already described, the conveyor carrying the several work-holders will be advanced intermittently to present the articles held in said workholders 10 successively at the printing station. These articles may be placed in the work-holders by the operator before the work-holders reach the printing station, as is well understood. At the printing station, the base plate 132 of the work-holder 15 engages the resiliently supported platform 143, so that the article, which is rotatably supported in the work-holder, is resiliently held in contact with the transfer surface of the cylinder at the time it receives the imprint therefrom. When 20 the transfer surface has completed the transfer of the imprint to the article, the carrier, or conveyor is advanced again, taking this article out of contact with the transfer cylinder and presenting another article to receive the imprint. The 25 articles which have been printed may be removed from the work-holder after the conveyor has left the printing station. This mechanism for intermittently presenting the articles to contact with the transfer surface, may also be used for intermittently presenting articles to contact with a 30 roller, or rollers, to apply a coating, or coatings, thereto. An example of such use will be described hereinafter.

By providing this mechanism by which the articles to be printed upon are rotatably supported and resiliently presented at the printing station, we have been able to print successfully directly upon bottles, jars, cans and like articles, having relatively unyielding walls or showing imperfections or irregularities in the surface portions. The resilient support for the work-holders, provided at the printing station, serves the purpose of compensating for variations in the thickness of the wall of an article, so that a perfect imprint 40 will be received notwithstanding such variations. As already indicated, the entire frame supporting the carrier may be delicately adjusted by the hand wheels 126, so that the several articles carried in the work-holders will be properly aligned 45 with the transfer surface of the cylinder in order to receive the impression. This machine operates quickly, efficiently and at low cost, and yet produces perfect imprints upon the walls of the bottles, jars, cans, or other articles of this nature. 50

Moreover, we have found that with this mechanism, and this process, it is possible to print labels and like decorative designs directly upon the walls of bottles of oval or other irregular shapes, the resilient support for the work-holder being 55 of such a nature as to permit a yielding to take care of such irregularities in shape of the article. Thus, our invention is applicable to articles of various non-cylindrical shapes, such as flat bottles, square or octagon shaped bottles, articles of frusto-conical form, such as tumblers, or articles having bulbous intermediate portions. In coating, these variations in shape can usually be taken care of by suitably controlling the resiliency of the coating surface of the coating roller, 60 as by choosing the appropriate composition for the material forming the coating portion of the roller, and by controlling the pressure exerted between the roller and the article presented to contact with it for coating. In printing, this 65

will involve suitable adjustments of the shape and movements of the transfer medium, as for example a continuous blanket, so as to insure that the blanket, or other transfer medium, will conform to the shape of the article in printing and that the surface speeds of travel of the article and the blanket during the period of contact in the different parts of their mutually contacting surfaces are the same.

10 In Figs. 30, 31 and 32, we have illustrated a modified form of apparatus embodying the underlying principles of our invention, which we have found particularly useful for applying a plurality of narrow, colored bands on the side walls of glass tumblers. These bands may be of the same or different colors on the same article and, for permanence, the stripes or bands may be of ceramic material, which can be applied as an ink or enamel and which will be indurated 20 and rendered permanent by subjecting the striped tumbler to a firing process.

The mechanism is shown in side elevation in Fig. 30 and comprises a frame consisting of the side members 200 supported by the legs 201. At 25 opposite ends of the frame, the shafts 202 and 203 are journaled in the side members 200. These shafts carry the spaced sprockets 204 and 205, respectively, around which the spaced conveyor chains 206 travel. Angle-bars 208, constituting 30 rails supporting the upper reaches of the conveyor chains 206, are secured to the side members 200 by the straps 207. The side members 200 are provided with inwardly extending flanges 209, at their lower edges, which constitute rails 35 supporting the lower reaches of the conveyor chains 206. The flanges 209 are curved upwardly at the ends, as shown at 210 and 211. A plurality of base plates 212 are pivoted to the conveyor chains 206, by the pins 213, and rails 208 40 and flanges 209 are wide enough so that they also support the base plates, as shown in Fig. 31. Each base plate 212 has a groove 214 formed in the inner face thereof and extending in the direction of travel of the conveyor.

45 A series of platforms 215 are provided, one being located opposite each of the units for coating or applying material to the surfaces of the tumblers. These platforms are so located as to cooperate with work-holders on the lower reach 50 of the conveyor. Each platform 215 has secured thereto a rib 216, fastened by the bolts 218 and having a pointed or tapered end 217. As the base plates 212 move into engagement with a platform, the tapered end 217 of the rib 216 enters 55 the slot 214 and guides the base plate into registry with the platform, as shown in Fig. 32. Each platform carries a pair of posts 219, which extend upwardly from the inner face of the platform, and the upper ends of these posts pass 60 through holes provided in the horizontal flanges of angles 220, which are fastened to the side members 200, as shown in Fig. 31. Nuts 221 are secured on the upper ends of the posts 219, above the angles 220, and springs 222 surround the 65 posts 219, and are compressed between the inner face of the platform 215 and the lower face of the horizontal flanges of angles 220. These springs resiliently urge the platform toward the unit which applies material to the surfaces of 70 the tumblers. Guide blocks 223 are fastened to the side members 200 and engage notches 224 formed in the ends of the platform, so as to restrain the platform 215 to vertical movement.

75 Upon each base plate 212 a work-holder is mounted, which rotatably supports one of the

articles to be decorated. Each work-holder comprises a base 225 secured to the base plate 212 by bolts 226. At one end of the base 225, there is secured an upright member 227. A supporting and positioning plate 228, having a flanged periphery receiving the base of a tumbler 229, or other article, is provided with a trunnion 230, journaled in the member 227. On the projecting end of the trunnion, there is fixed a driving roller 231, and a block 232 is fixed on the end of 10 the trunnion so as to hold it against displacement. To the other end of the base 225 there is fixed a member 233. A block 235 is hinged to this member, at 234, and a trunnion, or post, projecting from the supporting plate 236, is journaled 15 in the block 235. The supporting plate or disk 236 is flanged and receives the top of the tumbler, or other article, 229, supporting and positioning it. A block 237 fixed on the projecting end of said trunnion prevents displacement thereof in 20 its bearing.

It will be observed that the mechanism heretofore described is quite similar to the work-holding conveyor, or carrier, illustrated in Figs. 18 to 28, inclusive. In this case, however, the platforms 25 are located so as to cooperate with the lower reach of the conveyor and each platform is spring-pressed downwardly instead of upwardly. This is because the material-applying mechanism is located below the conveyor instead of above, as in Fig. 18.

A ratchet wheel 238 is fixed on the shaft 202 and actuated, to rotate the shaft intermittently, by a pawl 239 pivoted on the arm 240, which is journaled on shaft 202 and rocked by a link 241 35 connected to a pin eccentrically mounted on a gear 19 fast on the drive shaft 17 of one of the coating or material-applying units. Three of these units are shown in Fig. 30. They are substantially identical in construction with the coating mechanism shown in Fig. 1, with the exception of the work-holding carrier, and, therefore, corresponding reference numerals have been used. On the shaft 13, there is a roller 14 provided with a working surface 15 of gelatin or similar yielding 40 material. As shown in Fig. 31, the working surface comprises four narrow cylindrical surfaces, each of the width of a stripe to be applied to the tumbler, or other article, to be decorated. The material to be applied is fed to these working surfaces 15 by the rollers 26 and 28. Further description of these material-applying units is not needed, in view of the description of the apparatus shown in Fig. 1. As shown in Fig. 31, the working 50 surfaces on the several units are staggered, so as to contact with different portions of the tumbler. This is particularly useful where stripes of different colors are to be applied, in which case each of the three units shown may apply stripes of a particular color to the surface of the tumbler.

From the description of the parts given above, the operation of this mechanism should be readily understood. The tumblers, or other articles, to be decorated are placed in the work-holders by the operator in the manner which will be readily understood from the preceding description. The articles are rotatably supported in these work-holders and, as the conveyor is advanced intermittently, are presented in rolling contact with the working surfaces 15 of the material-applying units. When the conveyor is at rest, the work-holders presenting articles to contact with such working surfaces engage platforms 215 and hence are resiliently pressed, or urged, toward said 70 75

working surfaces, thus providing a means for maintaining resiliently a rolling contact between the working surfaces and the surfaces of the articles.

5 In cases where the articles are likely to be exposed to the action of solvents, which may remove the enamel coating usually employed, we propose to use ceramic inks. After the ground coating has been applied, and after the imprint 10 has been transferred to such ground coating in ceramic ink, we propose to subject the glassware, or other articles, upon which this decoration has been applied, to a firing operation, which will fix both the ground coating and the design applied thereto and prevent its being removed by the solvents used, for instance, in cleaning or other operations. Of course, this firing operation cannot be applied to articles which, by their nature, will not stand up under the heat. It is intended, 15 more particularly, for glassware. The ground coating, as well as the inks, should be of such character as to become indurated by the firing operation.

20 In the description set forth in the preceding portions of this specification and in the appended claims, we have referred to the invention as applied in decorating bottles, jars, cans and like articles. It will be understood that the invention is not limited in its application to hollow articles such as bottles, jars and cans. It is likewise applicable to the treatment of solid articles having a similar external appearance and shape, and, as ordinarily manufactured, lacking in conformity to a precise dimension or showing to a greater or lesser extent imperfections and irregularities in their surface portions. In other words, the expression "like articles" as used herein is to be understood as including any and all articles which present the same problems or one or more of the problems that are met with in printing upon and decorating bottles according to the known printing and lithographing methods.

25 We are aware that the process and apparatus herein described are susceptible of considerable variations without departing from the spirit of our invention, and, therefore, we claim our invention broadly as indicated by the appended claims.

30 Having thus described our invention, what we claim is:

1. In a machine for applying ink or like material to the surfaces of bottles, jars, cans and like articles, whether hollow or solid, the combination of a rotating transfer cylinder, a platform opposite said cylinder, an endless conveyor running over said platform, a plurality of work-holders mounted on said conveyor and each adapted to support rotatably one of the articles, and means for advancing the conveyor intermittently to present the articles successively to contact with the transfer surface of said cylinder.

2. In a machine for applying ink or like material to the surfaces of bottles, jars, cans and like articles, whether hollow or solid, the combination of a rotating transfer cylinder, a platform opposite said cylinder, an endless conveyor running over said platform, a plurality of work-holders pivotally mounted on said conveyor and each adapted to support rotatably one of the articles, and means for advancing the conveyor intermittently to present the articles successively to contact with the transfer surface of said cylinder.

3. In a machine for applying ink or like material to the surfaces of bottles, jars, cans and

like articles, whether hollow or solid, the combination of a rotating transfer cylinder, a platform opposite said cylinder, means for urging said platform resiliently toward the cylinder, an endless conveyor running over said platform, a plurality of work-holders mounted on said conveyor and each adapted to support rotatably one of the articles, and means for advancing the conveyor intermittently to present the articles successively to contact with the transfer surface of said cylinder.

4. In a machine for applying ink or like material to the surfaces of bottles, jars, cans and like articles, whether hollow or solid, the combination of a rotating transfer cylinder, a platform opposite said cylinder and resiliently urged toward it, an endless conveyor running over said platform, a plurality of work-holders pivotally mounted on said conveyor and each adapted to support rotatably one of the articles, and means for advancing the conveyor intermittently to present the articles successively to contact with the transfer surface of the cylinder.

5. In a machine for applying ink or like material to the surfaces of bottles, jars, cans and like articles, whether hollow or solid, the combination of a rotating transfer cylinder, a platform opposite said cylinder, an endless conveyor running over said platform, a plurality of work-holders mounted on the conveyor and each adapted to support rotatably one of the articles, inter-engaging means on the platform and work-holders for insuring registry of the work-holder on the platform and means for advancing the conveyor intermittently to present the articles successively to contact with the transfer surface of the cylinder.

6. In a machine for applying ink or like material to the surfaces of bottles, jars, cans and like articles, whether hollow or solid, the combination of a rotating transfer cylinder, a platform opposite said cylinder, means for resiliently urging said platform toward said cylinder, an endless conveyor running over said platform, a plurality of work-holders mounted on the conveyor and each adapted to support rotatably one of the articles, inter-engaging means on the platform and work-holders for insuring registry of the work-holder with the platform, and means for advancing the conveyor intermittently to present the articles successively to contact with the transfer surface of the cylinder while the work-holder carrying the article is in registry with the platform.

7. In a machine for applying ink or like material to the surfaces of bottles, jars, cans and like articles, whether hollow or solid, the combination of a rotating transfer cylinder, a frame, sprockets at opposite ends of the frame, a platform supported in said frame and resiliently urged toward said cylinder, means confining said platform to vertical movement with respect to said frame, an endless conveyor running around said sprockets and over said platform, a plurality of work-holders pivotally mounted on said conveyor and each adapted to support rotatably one of the articles, and means for advancing the conveyor intermittently to present the articles successively to contact with the transfer surface of the cylinder while the work-holder carrying the article is upon the platform.

8. In a machine for applying ink or like material to the surfaces of bottles, jars, cans and like articles, whether hollow or solid, the combination of a rotating transfer cylinder, a frame,

- 5 sprockets at opposite ends of the frame, a platform resiliently supported by the frame, means confining said platform to vertical movement with respect to the frame, an endless conveyor running around said sprockets and over the platform, a plurality of work-holders pivotally mounted on the conveyor and each adapted to support rotatably one of the articles, inter-engaging means on the platform and work-holders for insuring registry of the work-holder on the platform, and means for intermittently advancing said conveyor to present the articles successively to contact with the transfer surface of the cylinder while the work-holder carrying the article is in registry on the platform.
- 10 9. In a machine for applying ink or like material to the surfaces of bottles, jars, cans and like articles, whether hollow or solid, the combination of a rotating transfer cylinder, a frame, adjustable supports for the four corners of the frame, sprockets at opposite ends of the frame, a platform supported by the frame, and resiliently urged toward the cylinder, an endless conveyor running around said sprockets and over said platform, a plurality of work-holders mounted on the conveyor and each adapted to support rotatably one of the articles, and means for intermittently advancing the conveyor to present the articles successively to contact with the transfer surface of said cylinder while the work-holder carrying the article engages the platform.
- 15 10. In a machine for applying material to the surfaces of bottles, jars, cans and like articles, whether hollow or solid, the combination of an endless conveyor, a plurality of work-holders carried thereby and rotatably supporting the articles, a platform adapted to be engaged by said work-holders successively, resilient means acting on said platform, a material-applying unit located adjacent the conveyor and including a rotating transfer surface opposite said platform and toward which the platform is urged by said resilient means, means for feeding material to said transfer surface, and means for advancing the conveyor intermittently to present the articles successively to rolling contact with said transfer surface while the corresponding work-holder engages the platform.

11. In a printing machine for bottles, jars, cans and like articles, whether hollow or solid, the combination of a rotating transfer cylinder, a frame including a pair of side members, sprocket shafts journaled in said side members at opposite ends thereof, sprockets on said shafts, a pair of endless chains passing around said sprockets, a plurality of base plates pivoted to and located between said chains, work-holders mounted on said base plates and each adapted to receive one of the articles to receive the imprint, rails carried by the frame and supporting the base plates of the upper reaches of the chains, said rails being interrupted opposite the transfer cylinder, a platform carried by the frame and supporting the base plate opposite the cylinder, and means for advancing the chains to present the articles successively to contact with the transfer surface of said cylinder while the base plate of the work-holder carrying the article rests on said platform.

12. In a printing machine for bottles, jars, cans and like articles, whether hollow or solid, the combination of a rotating transfer cylinder, a frame including a pair of side members, sprocket shafts journaled in said side members at opposite ends thereof, sprockets on said shafts, a pair of endless chains passing around said sprockets, a plurality of base plates pivoted to and located between said chains, work-holders mounted on said base plates and each adapted to support rotatably one of the articles to receive the imprint, rails carried by the frame on which the base plates rest as they approach the cylinder, said rails being interrupted opposite the cylinder, a platform resiliently supported by the frame opposite the cylinder, means confining the platform to vertical movement with respect to the frame, inter-engaging means on the platform and base plates for insuring registry of the base plate on the platform, and means for advancing the chains to present the articles successively to contact with the transfer surface of said cylinder, while the base plate of the work-holder carrying the article is in registry on said resiliently supported platform.
